UNITED STATES PATENT OFFICE.

WILLIE LESLIE PURVES, OF WADDINGTON, NEW YORK.

FEED MECHANISM FOR SHINGLE-MACHINES.

SPECIFICATION forming part of Letters Patent No. 339,808, dated April 13, 1886.

Application filed January 15, 1886. Serial No. 189,755. (No model.)

To all whom it may concern:

Be it known that I, WILLIE LESLIE PURVES, of Waddington, in the county of St. Lawrence and State of New York, have invented a new and useful Improvement in Feed Mechanism for Shingle-Machines, of which the following is a specification, reference being had to the annexed drawings, forming a part thereof, in which—

10 Figure 1 is a plan view. Fig. 2 is a side elevation of a shingle-machine to which my improved feed mechanism has been applied.

Similar letters of reference indicate corresponding parts in the different figures of the drawings.

15 My invention consists in the construction and arrangement of parts, as will be herein-after fully described and specifically claimed.

A shingle-machine, A, is of the ordinary kind, having a saw, B, mounted on a mandrel and revolving in a vertical plane, and a swinging block-carrying frame or carriage, C, suspended from the arm D, and arranged to move above the concave bed-piece E and carry the block F, which is swung past the edge of the saw in the operation of removing a shingle from the block.

20 At the outer end of the curved bed E is journaled a pulley, a; and a rope, b, attached to the swinging frame C and extending over the pulley a, is secured at its lower end to a weight, c, which returns the swinging frame C to the position of starting.

Near the machine A is journaled a shaft, 25 G, carrying at one end a large pulley, d, and at the opposite end a friction-roller, e, which is located about opposite the swinging frame C.

In front of the saw B, and in the standard H, is pivoted a lever, I, which extends in one 30 direction from its pivot under the shaft G, and is forked to receive the roller f, which is journaled on a pin passing through the fork. The opposite end of the lever I reaches forward to a point near the swinging frame C, and is pressed upward by a spring, g, which tends to move the roller f away from the roller e.

35 By the side of the longer arm of the lever I, and near the swinging frame C, is placed a vertical hand-lever, J, which is pivoted to the floor, and is provided at about its mid-length with an arm, h, which reaches over the

top of the lever I. The upper end of the lever J is provided with a handle, i, which is grasped by the sawyer.

55

To a short arm, j, projecting from the bottom of the swinging frame C, is pivoted a bar, k, which passes between the rollers e f and rests normally upon the roller f.

The shaft G receives its motion directly 60 from the mandrel, or through a counter-shaft, l, and belts m n. The shaft G is constantly rotated in the direction indicated by the arrow, and when it is desired to move the swinging carriage C forward, to bring the block F 65 into engagement with the periphery of the saw, the sawyer presses forward the lever J, bringing the arm h into engagement with the lever I, pressing the roller f against the bar k, thus causing the bar k to bear upon the 70 periphery of the roller e with sufficient pressure to cause the bar k to be carried forward by friction, thus drawing the swinging frame C toward the saw, and bringing the block F under the action of the saw.

75

The rapidity with which the frame C is moved forward depends upon the amount of pressure exerted upon the bar k, as the shaft G is arranged to revolve with a speed sufficient for the fastest feed required, and when 80 a slow feed is required the roller e is allowed to slip more or less upon the bar k. After the shingle has been detached from the block F the lever I is released, when the weight c returns the swinging frame C and the bar k 85 to the point of starting, when the sawyer will move forward the block F into a position for another cut, when the operation just described will be repeated.

It is obvious that by extending the longer 90 arm of the lever I the lever, if desired, may be operated by the pressure of the foot, and the lever J may be dispensed with.

I am aware that it is not broadly new to feed the saw by a bar passed between two 95 friction-rolls; also, that the saw-feeding bar has been operated by rack and pinion, and I do not claim such constructions, broadly, as of my invention.

Having thus described my invention, what 100 I claim as new, and desire to secure by Letters Patent, is—

The feed mechanism for shingle-machines, consisting of the swinging frame C, hung in

front of the saw and having the arm *j* on its lower end, the curved bed-piece *E*, having a pulley, *a*, on its front end, the weighted rope connected to the frame *C* and passed over pulley *a*, the shaft *G* in rear of the saw, and provided with the drive-pulley *d* and the friction-wheel *e*, the standard *H*, the lever *I*, pivoted to the said standard and having the friction-wheel *f* pivoted on its rear end, the forward end extending to a point adjacent to the front of the machine, the spring *g*, tending

to separate the two friction-wheels, the lever *J*, having the bar *h* resting on the upper side of the lever *I* at its front end, and the bar *k* pivoted to the arm *j* of the swinging frame *C* and extended rearward between the two friction-rollers, all constructed and combined substantially as set forth.

WILLIE LESLIE PURVES.
